UNITED STATES PATENT OFFICE.

EDWARD A. ZOLLE, OF MINNEAPOLIS, MINNESOTA, ASSIGNOR TO MOORE CARVING MACHINE COMPANY, OF MINNEAPOLIS, MINNESOTA, A CORPORATION OF MINNESOTA.

REGULATOR FOR MULTIPLE-CYLINDER ENGINES.

1,065,491.

Specification of Letters Patent. Patented June 24, 1913.

Application filed June 3, 1911. Serial No. 631,185.

To all whom it may concern:

Be it known that I, EDWARD A. ZOLLE, a citizen of the United States, and resident of Minneapolis, in the county of Hennepin and 5 State of Minnesota, have invented certain Improvements in Regulators for Multiple-Cylinder Engines, of which the following is a specification.

This invention relates particularly to improvements in the multiple cylinder engine shown and described in Letters Patent No. 880,958, issued March 3rd, 1908, to Frank X. Bachle and John C. L. Krebs. In that 10 patent an engine is described having two or more cylinders, and in the case of a two-cylinder engine the charge is pumped into the combustion end of each cylinder by the piston of the other cylinder, and in the case of a three or more cylinder engine the charge 15 is pumped into the combustion end of each cylinder by the pistons of two or more cylinders of the series.

In using this engine I find it advantageous to regulate the amount of the charge that is 20 pumped into the combustion end of each cylinder, and I preferably, at the same time, regulate the supply of gas from the carbureter. In this way I am enabled to slow 25 down the engine and at the same time have 30 it run smoothly and evenly without missing any explosions, and economizing materially in the cost of fuel.

The invention consists generally in the constructions and combinations hereinafter 35 described and particularly pointed out in the claims.

In the drawings forming part of this specification, Figure 1 is a vertical, longitudinal section through the distributor of 40 an engine of the type designated and having my regulator applied thereto, Fig. 2 is a vertical section on line 2—2 of Fig. 1, Fig. 3 is a detail section of the regulator, Fig. 4 is an outline view showing means for simultaneously operating the regulator and the 45 valve of the carbureter.

In the drawings, 1, 2, 3 and 4 represent the cylinders of an engine embodying my improvement. Each of the pistons is 50 marked 5 and the enlargements at the lower ends are marked 5'. A rotating distributor or rotary valve 6 is arranged in a housing or valve casing 7, and this rotary valve is provided with ports arranged to register 55 with the ports of the cylinder. These parts

of the engine are all substantially as shown and described in said Patent No. 880,958.

I provide in connection with the rotary valve 6, a valve or regulator, which permits me to cut out at will the passage of the 60 charge to the combustion end of the cylinder from all but one of said cylinders. When this cut-off is closed each cylinder instead of receiving in its combustion chamber a charge 65 that is pumped into it by the pistons of two or more cylinders of the series, will receive only the charge pumped into it by one of the cylinders of the series. For this purpose I provide a suitable valve 9 located 70 preferably near the center of the rotary valve 6. As I have shown this device in the present drawing, a sleeve 8 forming a valve seat is located at or near the central point longitudinal of the rotary valve or distributor 6. The valve 9 is arranged to engage 75 the seat 8 and it is provided with a stem 10 that passes through a suitable stuffing box 13 at the end of the distributing chamber. A collar 12 is arranged upon the valve stem 10 and a suitable spring 11 surrounds the valve stem 10, and has one end bearing upon the sleeve 8 and the other 80 against the collar 12 on the valve stem 10. With this construction the spring tends to hold the valve 9 at all times against the seat. 85 A suitable operating lever 14 is arranged in position to engage the end of the valve stem 10. Any suitable means may be employed for operating the lever 14.

In running the engine ordinarily the lever 90 14 will be moved into position to engage the valve stem 10 and force the valve 9 off from the seat 8, thereby leaving a clear passage 95 from end to end of the rotary valve or distributor 6. By releasing the lever 14 the spring 11 will close the valve 9 upon its seat 8 and communication through the length of the rotary distributing valve will be prevented by said valve 9. When the valve 9 is open the distribution of the charge is the 100 same as described in said Patent No. 880,958, that is to say, cylinder No. 1 has its charge compressed therein by the pistons of cylinders 2 and 4; cylinder No. 2 by the pistons of cylinders Nos. 1 and 3; cylinder No. 3 by the pistons of cylinders Nos. 1 and 4 and cylinder No. 4 by the pistons of cylinders Nos. 2 and 3. When the regulator valve 9 is closed, as shown in Fig. 1 of the drawing, 105 the charge in cylinder No. 1 is compressed 110

therein by the No. 2 piston, and the charge in cylinder No. 2 is compressed therein by the No. 1 piston; the charge in cylinder No. 3 is compressed therein by the No. 4 piston 5 and the charge in cylinder No. 4 is compressed therein by the No. 3 piston. With the regulator valve closed, as stated, each cylinder will receive only half as much gas as it will with the regulator valve open, as 10 in the last named case each cylinder will receive the gas pumped into it by the pistons of two of the other cylinders. This construction is exceedingly simple and is easily applied to the rotary valves or distributors 15 of said Patent No. 880,958.

When it is desired to slow down the engine the valve 9 in the rotary valve or distributor 6 is closed by releasing the lever 14 and permitting the spring 11 to bring said valve 20 against its seat, and then each cylinder receives in its combustion chamber the gas pumped into it by only one piston, as hereinbefore set forth.

I find this device particularly advantageous where it is desired to run very slowly, 25 or where it is desired to leave an engine running idle. Only one-half as much gas will be supplied to each combustion chamber when the valve is closed as will be when this 30 engine is not provided with this valve, or as will be with this engine when the valve 9 is open.

I also find it advantageous, in using this device, to regulate the valve of the carbureter simultaneously with the opening or 35 closing of the regulator valve 9. In Fig. 4 of the drawings I have shown the outline of a carbureter connected to the distributing chamber of the engine, so as to furnish 40 gas for the cylinders. This carbureter is provided with a rod 15 which extends to a pedal or lever 16 in position to be under the control of the operator of the engine. A rod 17 also extends from the lever 14 to the same 45 pedal or operating lever. With this arrangement, when I close the valve 9, through the lever 14, I simultaneously adjust the carbureter so as to cut down the supply of gas to the engine, and when I open the 50 regulator valve 9 I open the carbureter valve also, and increase the supply of gas to the engine. By this means I materially economize in the use of fuel for the engine. When I am running the engine slowly and do not 55 need much power I cut down the supply of fuel and at the same time secure an even running of the engine with regular explosions in the cylinders. I find that the engine does not miss any explosions and that with 60 this device a two-cycle engine can be throttled with much better results than have heretofore been obtained. When the regulator valve is closed the space that is to be filled by the gas driven out of a cylinder by the 65 enlargement on its piston, is very much re-

duced. Hence, a greater compression of the charge can be obtained than would be possible by throttling the engine through reducing the delivery of gas at the carbureter alone.

While I prefer to use in conjunction with the regulating valve the means described for regulating the supply of gas from the carbureter, I do not limit myself to the use of this last named feature, as important advantages will result from the use of the regulating valve alone.

I do not limit myself to the details of construction, as the same may be varied in many particulars without departing from my invention.

I claim as my invention:

1. The combination, with an internal combustion engine having more than two cylinders, each provided with a combustion and pumping chamber and in which the charge is pumped into the combustion end of each cylinder by the pistons of a plurality of the other cylinders of the series, of means for cutting out at will the passage of the charge to the combustion end of a cylinder from all but one of said other cylinders, whereby each cylinder will receive its charge from the pumping chamber of one of the other cylinders only.

2. The combination, with an internal combustion engine having more than two cylinders, each provided with a combustion and a pumping chamber and in which the charge is pumped into the combustion end of each cylinder by the pistons of a plurality of the other cylinders of the series, of means for cutting out at will the passage of the charge to the combustion end of a cylinder from one or more of the other cylinders.

3. The combination, with an internal combustion engine having more than two cylinders each provided with a combustion and a pumping chamber, and in which the charge is pumped into the combustion end of each cylinder by the pistons of a plurality of the other cylinders of the series, of a carbureter, means for cutting out and permitting at will the passage of the charge to the combustion end of a cylinder from one of the other cylinders, and means for simultaneously regulating the discharge of gas from the carbureter.

4. The combination, with a multiple cylinder internal combustion engine in which each cylinder is provided with a combustion chamber, and a pumping chamber, of a rotary distributing valve provided with passages adapted to receive the explosive mixture from the carbureter and lead it into said pumping chambers, and having also a longitudinal passage arranged to receive the explosive mixture from said pumping chambers and to lead the same to said combustion chambers, and dividing means arranged

- in said discharge passage and operable at will to permit or prevent the mixture in one portion of said passage entering the cylinder communicating with the opposite portion, substantially as described.
5. The combination, with a multiple cylinder internal combustion engine in which each cylinder is provided with a combustion chamber and a pumping chamber, of a rotary distributing valve having passages arranged to receive the explosive mixture from the carburetor and to direct it to said pumping chambers, and having a longitudinal distributing passage, which receives the explosive mixture from said pumping chambers, and which communicates in turn with the combustion chamber of each cylinder in its respective order of ignition, and means for closing at will said distributing passage at a point near the middle thereof, preventing the gases from one end of said passage from entering the combustion chambers communicating with the other end thereof, substantially as described.
- 10 6. The combination, with a multiple cylinder internal combustion engine, in which each cylinder is provided with a combustion chamber and a pumping chamber, of a rotary distributing valve, having passages arranged to receive the explosive mixture from the carburetor and to direct it into the pumping chambers of the cylinder, and having a passage which receives the mixture from said pumping chambers and directs it to the combustion chamber of each cylinder in its respective order of ignition, and means provided in connection with said passage whereby the mixture in one end of said passage may be permitted to enter, or prevent it from entering the other end thereof.
- 15 7. In an internal combustion engine, a plurality of cylinders, a valve chamber common to all of the cylinders and having passages leading thereto, rotary means in said valve chamber for controlling said passages and having a plurality of charge distributing chambers each of which is common to the passages of a portion only of the cylinders, and means operable to open communication between said distributing chambers.
- 20 8. In a multiple cylinder internal combustion engine having its cylinders provided with pumping and combustion chambers, the combination of a valve chamber common to all of said cylinders and having passages leading to the chambers therein, a rotary valve in said valve chamber for controlling all of said passages, said valve having inner and outer chambers, one serving as a gas supply chamber and the other as a gas distributing chamber, the distributing chamber being divided into a plurality of separated compartments each of which is common to the passages of a plurality of said cylinders,
- 25 9. In a multiple cylinder engine having its cylinders provided with pumping and combustion chambers and passages leading thereto, the combination of a rotary valve common to all of said chambers and having a gas supply chamber and a gas distributing chamber and ports for opening communication between said chambers and said passages to control the pumping of charges into the pumping chambers and the distribution thereof from such pumping chambers to the combustion chambers, a partition in the distributing chamber dividing it into compartments to cause the cylinders to work in pairs, a passage to open communication between the compartments of the distributing chamber, and a valve in said passage for controlling the passage of the charges therethrough.
- 30 10. In a multiple cylinder engine having its cylinders each provided with pumping and combustion chambers having passages leading thereto, the combination with a rotary valve which is common to all of said chambers to control the admission of charges to the pumping chambers and the distribution of charges to each combustion chamber from a plurality of pumping chambers of the other cylinders, and a throttle controlling the admission of charges to said valve, of means separating the charge distributing portion of said valve into a plurality of compartments which cause the cylinders to work in pairs, a passage opening communicating between such compartments, a valve for opening and closing said passage, and mechanism for operating said throttle and said last mentioned valve in unison.
- 35 11. In a multiple cylinder engine having its cylinders provided with pumping and combustion chambers having passages leading thereto, a valve casing forming a chamber which is common to all of said cylinder passages, a rotary valve mounted in said chamber and having a supply chamber provided with ports for registering with the pumping chamber passages and having a distributing chamber provided with ports for registering with all of said passages at predetermined intervals during a rotation of the valve, said distributing chamber having at least one partition therein dividing it into compartments to cause charges to be distributed from one to another of the cylinders in pairs, a passage to open communication between the compartments of its distributing chamber, a valve located in said passage, a throttle for controlling admission of gas to said supply chamber, and manually controlled means operable to open and close said throttle and said last mentioned valve.
- 40 12. In a multiple cylinder internal com-

- bustion engine having its cylinders provided with pumping and combustion chambers, the combination of a valve chamber common to all of said cylinders and having passages leading to the chambers therein, a rotary valve in said valve chamber for controlling all of said passages, said valve having inner and outer chambers, one serving as a charge-supply chamber and the other as a charge-distributing chamber, the distributing chamber being divided into a plurality of separate compartments, each of which is common to the passages of a plurality of said cylinders.
13. In a multiple cylinder engine having its cylinders provided with pumping and combustion chambers and passages leading thereto, the combination of a rotary valve

common to all of said chambers and having a charge-supply chamber and a charge-distributing chamber and ports for opening communication between said chambers and said passages to control the pumping of charges into the pumping chambers and the distribution thereof from such pumping chambers to the combustion chambers, and at least one partition in the distributing chamber dividing it into compartments to cause the cylinders to work in pairs.

In witness whereof, I have hereunto set my hand this 31st day of May 1911.

EDWARD A. ZOLLE.
